ARTICLE SUPPORT

Application filed September 24, 1929. Serial No. 394,858.

This invention relates to supports, and more particularly to supports that are adapted for holding articles in or adjacent to windows, or between windows of buildings.

Among the objects of the present invention is the production of supports that may be readily adjusted to windows of different widths, or spaces of different widths between windows, and to different depths of window sills, so that the supports may be readily used wherever desired, either in windows or between windows.

Other and further objects and advantages will appear from the more detailed description set forth below, it being understood, however, that this more detailed description is given by way of explanation only, and not as limiting, since various changes may be made in this disclosure by those skilled in the art without departing from the scope and spirit of this disclosure.

In connection with that more detailed description, there is shown illustratively in the drawings, in

Figure 1 a perspective view of a support adapted to hold an article in or near a window; in

Figure 2 an end elevation of the support of Figure 1 shown in position in a window structure; in

Figure 3 a perspective view of the means for securing the arms of the support together; in

Figure 4 a perspective view of the block which carries the means for securing the support in the window sill; in

Figure 5 a perspective view of a modified form of support which may be used for holding articles between windows; in

Figure 6 an end elevation of the support of Figure 5 shown in position in a window structure; in

Figure 7 a perspective view of the means for holding the arms together; and in

Figure 8 a perspective view of the block which may be utilized in connection with the means for securing the support of Figure 5 between windows.

As illustrated in the drawings, the supports covered by the present invention are

desirably formed with side portions provided with arms extending from said side portions, the arms being adjacent to each other, and means being supplied for securing the arms together, and also there being means for attaching the support to a supporting structure. Desirably the support may be formed of a metallic element such as wire, but any other desired material may be utilized. The invention is further illustrated in the drawings as being made with side portions of substantially similar geometric contour, which side portions are also parallel to each other, but it will be understood that it is not essential that the contours of the side portions be identical, and further that they need not be parallel, although this is the preferred form of the invention.

Turning to a consideration to the form of support illustrated in Figures 1 to 4, particularly designed for use in a window, the support takes the form of two side portions

1, 1 formed of a length of metallic element, with upper portions 2, 2, lower portions 3, 3, front element 4 and rear elements 5, 5. The

rear elements are desirably bent backwardly as shown at 6, 6, so that the lower portions

7, 7 of each of the side portions may rest against the wall W while the upper portions 5, 5, of the rear element are spaced

from the wall W. That portion of the metallic element which forms the portion 5 of the rear element continues upwardly and is bent over the upper element 2 and then

downwardly, as shown at 8, with an annular bend at 9 to form the arm 10, which extends substantially at right angles from the plane of the side portion 1. The end of the metallic element which forms the upper

element 2 extends rearwardly to form an end portion 11, provided with an engaging hook 12. The engaging hooks 12, 12 are

adapted to seat in a block B shown specifically in Figure 4. The block B may be provided with an extending lug 13, carrying an aperture 14, in which the hook 12 is seated. Any desired means, such as a set screw, may be utilized for securing the hook 12 in the aperture 14 of the block B. The block B is further desirably provided with an aper-

100

ture 15 running transversely of the block and preferably clear through the same, so that it is provided to receive an attaching rod 16 provided with a hooked end 17. The attaching rod 16 is held in the aperture 15 by means of a set screw 18, which passes into a threaded opening 19 in the block B at right angles to the aperture 15, the threaded opening 19 allowing the set screw 18 to be adjusted in the opening 19, so that the set screw 18 impinges against the connecting rod 16 for securing that connecting rod rigidly in the opening 15. The hooked end 17 on the connecting rod 16 is adapted to engage the groove G of the sill end of the window just above the ledge L thereof, and in this manner the support is held in position immediately in front of the window at the lower portion thereof.

20 The arms 10, 10 which extend inwardly from the side portions 1, 1, are placed closely adjacent to each other as shown in Figure 1 of the drawings, and may be secured together by any desired attaching means. For this purpose, a block C may be provided having a transverse opening or aperture 20 which extends entirely through the block C, the opening 20 being of such size as to accommodate the two arms 10, 10. At right angles to the opening 20, the block C is provided with a threaded opening 21 adapted to receive a set screw 22, so that the set screw may be forced down into the opening 21 until it impinges against the arms 10, 10 contained within the opening 20, and the arms 10, 10 will thus be secured rigidly together. For this purpose the opening 21 extends through the block into the opening 20.

25 The use of the support set forth in Figures 1 to 4 of the drawings is readily understood from the description given above. The hook members 17, 17 are engaged in the opposite grooves G of the end sill F of the window, so that the support is held at the ledge L of the window with the rear element 7 of the end portions of the support resting against the wall W. Due to the set screw 18 and the attaching rod 16, the support may be adjusted readily to varying distances between the outer ledge of the window and the groove G of the sill. Furthermore, the set screw 22 in the block C allows for ready adjustment of the width of the support by movement of the arms 10, 10 within the opening 20 of the block C. In this manner, the support may be adjusted readily for varying depths of window frames, and also for varying widths of windows. Instead of using the blocks B, B with this structure the hooks 12, 12 on the portions 30 11, 11 of the upper elements of the side portions may be utilized for attachment to the window sill, but this does not allow for adjustment of the support to accommodate varying distances between the outer ledge of the window and the grooves G in the sills,

so that the preferred modification is as illustrated where the blocks B are utilized for obtaining the desired adjustment. The blocks B and C may be made of any desired material. While two blocks C, C are illustrated, one near each end of the arms 10, 10, obviously one such block C might be utilized if desired, or there may be any number of the blocks C placed on the arms 10, 10. Obviously any other securing means for the arms 10, 10 might be utilized in place of the blocks C, C, and also other attaching means might be utilized in lieu of the blocks B, B for attaching the support in the window. The support illustrated lies partially wholly below the window frame, so that no interference with the use of the window is necessitated. The article to be supported may be placed upon the lower elements 3, 3 of the side portion 1, 1, or may be placed on the upper portions 2, 2, of the side portions 1, 1. Instead of placing the articles directly on the aforementioned elements of the side portions, shelves may be placed on such elements, and the articles to be supported may be placed upon such shelves. Figure 2 illustrates the support of an article A upon the lower elements 3, 3 of the side portions.

35 The form of support illustrated in Figures 5 to 8 is primarily designed for use between windows to overcome certain city ordinances frequently effective, which provide that obstructions shall not be placed directly in front of windows. The support is similar in its general nature to that illustrated in Figures 1 to 4. The side portions 1', 1' are desirably formed with substantially horizontal upper elements 2', 2', and rear elements 5', 5'. The portion of the metallic element forming the rear wall is bent as illustrated at 6' in a rearward direction, and then downwardly to form the element 7' adapted to engage against the wall W'. In this manner, the portion 7' supports the side portions away from the wall W'. The upper element 2', 2' of each side portion is continued rearwardly to form a connecting rod 11' having a hooked end 12' adapted to be received by the block B'. The block B' is provided with an aperture 14' to receive the hooked end 12' of the element 11', the hooked end 12' being held rigidly in the block 14' in any desired manner. The block B' is preferably provided with a transverse opening 15' extending through the block from one face to the other for the reception of a connecting rod 16' provided with a hooked end 17' adapted to engage in the groove G' of the sill S' of the window. The attaching rod 16' is held rigidly in the block B' by means of a set screw 18' received by the threaded aperture 19' in the upper portion of the block B', the threaded opening 19' extending through the block to the aperture 15'. The arms 10', 10' extend inwardly from each side portion of the support, the arms

preferably extending above the upper elements 2', 2' of the side portions. The arms 10', 10' are secured together in any desired manner as by means of the blocks C', C'. The blocks C', C' carry a transverse opening 20' for reception of the arms 10', 10', the arms being held in the block against movement by means of the set screw 22' which passes through the threaded opening 21'. The opening 21' extends through the side of the block into the opening 20', so that the set screw may be forced down against the arms 10', 10' in the opening 20' and prevent movement of the arms when set in position.

As stated above, the form of support illustrated in Figures 5 to 8 is primarily designed for use between windows, the hooked ends 17', 17' engaging grooves G', G' of adjacent windows. Instead of utilizing the blocks B', B' with their associated attaching elements, the hooks 12', 12' may be directly engaged in grooves G', G' of the adjacent window sill, but it is more desirable in order to secure adjustment to utilize the blocks B', B' with their associated elements. While two blocks C', C' have been illustrated, only one such block could be utilized, although two form a desirable number, and there may be a greater number of such blocks if desired. Due to the attaching rod 16' with the hooked end 17' thereon, the support is readily adjusted to varying distances between the grooves G' of the sill S' and the ledge of the window, and further, due to the fact that the block C' may be readily loosened on the arms 10', 10' to allow for adjustment to varying widths, the support is readily placed in position between windows of any desired spaced distance. The support, therefore, allows for ready adjustment to any desired adjacent window. The article A' may be supported on the upper elements 2', 2' of the side portions 1', 1', or a shelf may first be placed on the upper elements 2', 2' on which the article may then be supported.

The form of article support illustrated in Figures 1 to 4 constitutes a preferred form of the invention for a number of reasons. The support illustrated in Figures 1 to 4 is utilizable in more relationships than is that of Figures 5 to 8. In connection with the structure illustrated in Figures 1 to 4, particular attention may be called to the fact that the element 5 extends over the element 2, and then is bent downwardly to provide the element 8, which is further continued by bending at the point 9 to form the arm 10. For reception of the bend between the elements 5 and 8, the element 2 has a recess or groove formed in it, as by bending, to receive the bend between the elements 5 and 8 so that the parts are locked together, and relative movement between them is prevented. Furthermore this offset in the element 2 which receives the bended portion of the wire

between the elements 5 and 8, serves to place the bended portion of the wire between elements 5 and 8 on substantially the same plane as the element 2, and consequently there is no obstruction to any article or shelf placed on the element 2. The element 8 not only is bent downwardly, but also desirably is bent forwardly, so that the block C is held away from the window ledge L. Furthermore, as illustrated in the drawings, the element 11 is desirably given a bend upwardly so that the hooked portion 12 in the block B enables the block B to position properly with respect to the window ledge L. The upward bend of element 11 also has an additional function in that it tends to throw the weight on the element 11 at just about the edge of the ledge of the window, and thus compensates for the thickness of the block B below the hook 17.

The block B having the offset portion 13 enables the element 16 to clear any object placed upon the elements 2, 2.

The structure illustrated in Figures 1 to 4, which is, as stated, the preferred form of the invention, enables a support of this character to be used in any of four positions, namely in a window inside of the house, in a window outside of the house, and in the space between two windows whether inside or outside of the house. The hooks 12 may be bent outwardly when used in a window, and inwardly when used in the space between two windows.

Of course, the structure shown in Figures 5 to 8 may be modified to follow the structure shown in Figures 1 to 4 constituting the preferred form of the invention by supplying forwardly bent elements to provide portions 8 in the structure shown in Figures 5 to 8, and similarly the blocks B and B' may be used with the structures shown either in Figures 1 to 4 or 5 to 8 respectively.

Having thus set forth my invention, I claim:

1. A support comprising two side portions, an arm extending from each side portion, the arms being adjacent to each other, and means for securing the arms together, in which the side portions are provided with means for attaching the support to a supporting body, such attaching means comprising a block attached to each side portion, a transverse opening in said block, an attaching rod passing through the transverse opening, and a set screw in the block ending in the transverse opening for securing the attaching rod in position.

2. A support comprising two side portions of similar geometric contour, each side portion being formed of a length of metallic element, one end of the metallic element extending rearwardly of the side portion to provide means for attaching the support to a supporting body, and the other end of each

- of the metallic elements forming the side portions extending angularly to the side portion to form arms, the arms lying adjacent to each other, and means for securing the arms together, in which the side portions carry means for attaching the support to a supporting body, such attaching means comprising a block carried by each side portion, a transverse opening in each of said blocks, an attaching rod passing through the said transverse opening, a set screw in the block ending in the transverse opening for securing the attaching rod in position, the means for securing the arms together comprising a block provided with a transverse aperture through which the arms pass, a threaded aperture in the block ending adjacent the opening for the arms, and a set screw in the threaded opening adapted to hold the arms in the securing block.
3. A support comprising two side portions of similar geometric contour, each side portion being formed of a single length of metallic element, one end of the metallic element extending rearwardly of the side portion to provide means for attaching the support to a supporting body, and the other end of each of the metallic elements forming the side portions extending angularly to the side portion to form arms, the arms lying adjacent to each other, and means for securing the arms together.

LOUIS M. RICHARD.
